CANE MILLS

Philip V. Tippet, Ansonia, Conn., assignor to Farrel-Birmingham Company, Incorporated, Ansonia, Conn., a corporation of Connecticut

Application October 18, 1954, Serial No. 462,736

11 Claims. (Cl. 100—165)

This invention relates to cane mills and more particularly to a so-called three-roll stand of a cane mill, the stand employing a cane roll, a bagasse roll, and a top roll.

It is well established that a definite ratio should be maintained between the opening between the top roll and the cane roll on the one hand and the top roll and bagasse roll on the other hand, and it has been found that a most satisfactory arrangement is that wherein the ratio between the cane and bagasse openings is approximately 2 to 1.

However, it is customary to so mount the top roll so that it floats to some extent, this being necessary in order to insure that the full hydraulic pressure on the rolls is obtained. It will be understood that the top roll is urged toward the cane and bagasse rolls by hydraulic pressure so that while the top roll is permitted to float, this pressure will always be maintained. This floating of the top roll makes allowance for the thickness of the blanket of cane passing through the mill.

Even though the rolls be originally set very carefully to provide the proper ratio between the cane and bagasse roll openings, this ratio is, of course, upset when the top roll moves against the hydraulic pressure applied thereto. If, however, the top roll is so mounted that it would tend, when it rises, to move toward the bagasse roll, which might tend to maintain the initial ratio between the roll openings, the horizontal thrust of the top roll box is accentuated, and hence such a correction for the disturbance in the proper ratio is impractical.

In order to counteract the horizontal thrust to which the top roll is subjected, inclined housings have been employed in which the top roll is mounted, the inclination being in the direction of the entering cane. While such inclined housings relieve the side or horizontal thrust referred to, they have the disadvantage of upsetting or disturbing the ratio between the cane and bagasse roll openings even more than the vertical housings.

As it is desirable to employ such inclined housings, however, in order to counteract the horizontal thrust referred to, the present invention contemplates the use of such inclined housings combined with means for automatically moving the top roll forwardly (that is, in the direction in which the cane travels) as it rises so that a fixed ratio of cane to bagasse roll openings is constantly maintained. To this end the housing for the top roll is inclined rearwardly or toward the entering cane so that the journal box of the top roll slides in the housing jaws as it rises along a resultant of the forces developed by a 2-to-1 opening ratio, and at the same time means is provided to move the housing forwardly in an amount proportional to the rise of the top roll so that the 2-to-1 roll opening ratio (or any other ratio for which the rolls are set) will not be disturbed.

As illustrated in the drawings, the top roll is mounted in its own housing entirely separate from the lower rolls, this housing being permitted to swing about a pivot at its lower end through a relatively short arc. A plunger is provided in the main frame of the mill to act upon the top

2

roll housing and move it laterally in response to any rising or falling movement of the top roll in its housing. As illustrated, this movement of the housing of the top roll is effected hydraulically. A closed hydraulic circuit is provided between a ram actuated by movement of the top roll and a ram which acts on the pivoted housing of this roll. With such a construction adjustment may readily be made for any desired ratio of cane and bagasse roll openings by changing the effective diameter of the cylinder in which one of the plungers operates as will be more fully explained hereinafter.

One object of the present invention is to provide a three-roll cane mill having means for maintaining a constant ratio between the cane and bagasse roll openings.

A still further object of the invention is to provide a cane mill having a top roll, a cane roll and a bagasse roll with means for permitting the top roll to float and means for moving the top roll horizontally to maintain a constant ratio between the cane and bagasse roll openings, the last means being responsive to floating movement of the top roll.

Still another object of the invention is to provide a three-roll cane mill having a top roll, a cane roll, and a bagasse roll with a top roll housing mounted in the roll stand for pivotal or swinging movement, and means for moving the housing horizontally about such pivot in response to vertical movements of the top roll, the latter being mounted to float in its housing.

To these and other ends the invention consists in the novel features and combinations of parts to be herein-after described and claimed.

In the accompanying drawings:

Fig. 1 is a side elevation of a roll stand of a cane mill embodying my invention;

Fig. 2 is a top plan view thereof;

Fig. 3 is a sectional view on line 3—3 of Fig. 2; and

Fig. 4 is a sectional view on line 4—4 of Fig. 1.

To illustrate a preferred embodiment of my invention I have shown a cane mill comprising a pair of spaced side frames or housings 10 and 11. In these housings are mounted the cane roll 12 and bagasse roll 13, the necks of these rolls being mounted in journals 14 and 15 respectively according to the usual custom. The roll journals may be held in place in the side frames by caps 16 and 17 pivoted to the frame at 18 and 19, the caps being held in place by a through bolt 20. Lateral adjustment of the journal boxes 14 and 15 may be effected by the adjusting screws 21 and 22. As the parts so far described are substantially of the usual form, a more detailed description will be unnecessary.

The roll stand is also provided with a top roll 23, each neck 24 of which is mounted in a journal box 25. This box is mounted for sliding movement in a direction inclined to the vertical in a top roll housing 26.

Each of the roll housings 26 is constructed independently of the side housings 10 or 11 but extends downwardly therethrough, as shown in Figs. 3 and 4. As shown in the latter figure, each housing 26 is provided with a shouldered portion 27 adapted to rest on flanges 28 of the corresponding side housings so as to be supported from below. The contacting surfaces between the parts 27 and 28 may be slightly arcuate in form, as shown in Fig. 3, in order to permit a rolling or pivotal movement of the housing 26 about its lower end.

An adjusting screw 29 is threaded into the lower end of each of the housings 26, the upper end of each screw abutting against the flattened lower face of a pin 30 in each of the side housings to adjustably limit upward movement of the housing 26 during operation.

As shown in Fig. 1, the upper portion of each of the housings 26 consists of spaced wall elements 32 and 33,

the journal box 25 being, as stated, slidably mounted therebetween. Above the journal box is a spacer plate 34 engaged by the lower end of a block 35, the upper end of this block bearing against a piston or ram 36, this ram being slidably mounted in a cylinder 37 locked in place between the members 32 and 33 by the key 38. The cap 39 formed integrally with the cylinder 37 rests upon the upper edges of the housing. It will be understood that the cap and cylinder may be moved laterally or vertically into position between the members 32 and 33 with the bars 38 resting against the shoulders 40 formed on these members.

The cylinder 37 is provided with a cylinder head 41 removably mounted in the cylinder 37 by a bayonet joint arrangement, and it will be understood that fluid pressure is introduced in the space 42 between the head 41 and the upper end of the ram 36 in order to provide suitable hydraulic pressure upon the top roll 23 as is required for obtaining proper extraction of the cane juice and allow the top roll to float to a certain extent.

An auxiliary or small extension ram 44 is provided upon the main ram 36, which extension ram operates in a cylinder 46 provided in the head 41 of the main cylinder. The cylinder 46 is connected by the conduit 47 with the cylinder 48 provided upon the corresponding main side housing, as shown in Fig. 3. The cylinder 48 is provided with a liner 49, and within this cylinder is movably mounted a ram 50, the outer end of which acts against the housing 26 of the top roll.

The movement of the housing 26 is resisted by a spring-pressed plunger 52 mounted in the main housing on the side of the housing 26 opposite the ram 50, the plunger 52 being urged toward the housing 26 by a spring 53, the tension of which is adjustable by means of the adjusting screw 54.

The usual turn plate 55 (Fig. 4) may be provided between the cane and bagasse rolls, this plate being adjustable by means of the crank pin 56.

It will be understood that hydraulic pressure is introduced into the cylinder 37 in the usual manner to maintain pressure upon the top roll. It will also be seen that the cylinders 46 and 48 together with the connecting conduit 47 constitute a closed hydraulic circuit which will be kept full of fluid such as oil. This circuit is ordinarily connected to a source of hydraulic pressure merely to replace possible leakage.

With this construction as the top roll rises, for example, the auxiliary ram 44 will reduce the volume of fluid in cylinder 46, forcing the fluid into cylinder 48 behind the ram 50. This in turn forces the ram to the right, as shown in Fig. 3, thus moving the top roll laterally or in a substantially horizontal direction toward a vertical plane passing through the axis of the bagasse roll 13. The capacity of the cylinders 46 and 48 is so proportioned that the movement of the housing 26 laterally in response to an upward movement of the roll 23 is such as to maintain constant the ratio between the cane and bagasse openings.

The pressure maintained in the cylinders 46 and 48 is such as to counteract any pressure upon the housing 26 effected by the frictional resistance of the turn plate or the driving effect of the gearing upon the rolls. It will also be understood that if a ratio other than a 2-to-1 ratio is desired between the cane and bagasse roll openings, it is only necessary to introduce a liner 49 of different dimensions into the cylinder 48 in order to increase or decrease the ratio between the capacity of this cylinder and the cylinder 46. As the amount of fluid within the closed hydraulic system embracing these cylinders remains constant, the movement imparted to ram 50 by any given movement of ram 44 will be constant so long as the dimensions of the cylinders remain constant so that any desired ratio may be maintained between the cane and bagasse roll openings.

While I have shown and described a preferred embodiment

ment of my invention, it will be understood that it is not to be limited to all of the details shown, but is capable of modification and variation within the spirit of the invention and within the scope of the claims.

5 What I claim is:

1. A cane mill having a cane roll and a bagasse roll, and housings in which the ends of said rolls are mounted, a top roll, and housings in which said top roll is mounted, said last-named housings being mounted for lateral movement relatively to the first housings, said top roll being mounted for rising and falling movement relatively to its housings, and means responsive to said last-named movement to effect lateral movement of the top roll housings.

10 2. A cane mill having a cane roll and a bagasse roll, and housings in which the ends of said rolls are mounted, a top roll, and housings in which said top roll is mounted, said last-named housings being mounted for lateral movement relatively to the first housings, said top roll being mounted for rising and falling movement in its housings, means responsive to said last-named movement to effect lateral movement of the top roll housings, said means comprising a cylinder on each of said first-named housings, and a piston in each of said cylinders acting on said top roll, and means controlled by rising and falling movements of the top roll for introducing fluid pressure into said cylinders.

15 3. A cane mill having a cane roll and a bagasse roll, and housings in which the ends of said rolls are mounted, a top roll, and housings, each having a portion in which said top roll is mounted, said last-named housings being mounted for lateral movement relatively to the first housings, said top roll being mounted for rising and falling movement in its housings, hydraulic means responsive to said last-named movement to effect lateral movement of the top roll housings, said top roll housing portions being inclined with respect to the vertical, and hydraulic means for exerting downward pressure upon said top roll.

20 4. A cane mill having cane and bagasse rolls, and end housings in which each end of each of said rolls is mounted, top roll housings and a top roll mounted therein for rising and falling movement toward and from the cane and bagasse rolls, each of said top roll housings being rockingly mounted with respect to one of said first-named housings for lateral movement with respect thereto, a cylinder carried by each of the top roll housings, a piston in each of said cylinders moved by rising movements of the top roll and means actuated by movement of said pistons for effecting lateral movements of said top roll housings in response to, and in an amount proportional to, the rising and falling movements of said top roll.

25 5. A cane mill having cane and bagasse rolls, and end housings in which each end of each of said rolls is mounted, top roll housings and a top roll mounted therein for rising and falling movement toward and from the cane and bagasse rolls, each of said top roll housings being rockingly mounted with respect to one of said first-named housings for lateral movement with respect thereto, means for effecting lateral movements of said top roll housings in response to, and in an amount proportional to, the rising and falling movements of said top roll, said means comprising a cylinder supported by said first-named housing having a piston therein acting upon the top roll housing, a second cylinder in said top roll housing having a piston therein moved in response to movements of the top roll, and conduit means connecting said cylinders to provide a closed hydraulic circuit therebetween.

30 6. A cane mill having cane and bagasse rolls, and end housings in which each end of each of said rolls is mounted, top roll housings and a top roll mounted therein for rising and falling movement toward and from the cane and bagasse rolls, each of said top roll housings being rockingly mounted with respect to one of said first-

named housings for lateral movement with respect thereto, means for effecting lateral movements of said top roll housings in response to, and in an amount proportional to, the rising and falling movements of said top roll, said means comprising a cylinder supported by said first-named housing having a piston therein acting upon the top roll housing, a second cylinder in said top roll housing having a piston therein moved in response to movements of the top roll, conduit means connecting said cylinders to provide a closed hydraulic circuit therebetween, and means for exerting downward pressure upon said top roll comprising a cooperating piston and cylinder, and said second piston being formed integrally with said last-named piston.

7. A cane mill having a cane roll, a bagasse roll and a top roll, there being openings between the top roll and the cane roll on the one hand and the top roll and the bagasse roll on the other hand, between which the cane passes, means for mounting said top roll for rising and falling movements in a direction generally toward and from said cane and bagasse rolls, and means to move said top roll laterally to maintain the ratio between said openings substantially constant regardless of movements of said top roll, said means comprising a cylinder, a piston in said cylinder actuated by rising movement of the top roll, and means responsive to movement of said piston to move the top roll laterally in an amount proportional to the movement of the piston, said last-named means comprising a second cylinder connected to said first cylinder and a piston in said second cylinder, and a housing for the top roll against which said last-named piston bears.

8. A cane mill having a cane roll, a bagasse roll and a top roll, there being openings between the top roll and the cane roll on the one hand and the top roll and the bagasse roll on the other hand, between which the cane passes, means for mounting said top roll for rising and falling movements in a direction generally toward and from said cane and bagasse rolls, and means to move said top roll laterally to maintain the ratio between said openings substantially constant regardless of movements of said top roll, said means comprising a cylinder, a piston in said cylinder actuated by rising movement of the top roll, means responsive to movement of said piston to move the top roll laterally in an amount proportional to the movement of the piston, a housing having a portion in which said top roll is mounted, said housing portion being inclined with respect to the vertical.

9. A cane mill having a cane roll, a bagasse roll and

a top roll, there being openings between the top roll and the cane roll on the one hand and the top roll and the bagasse roll on the other hand, between which the cane passes, means for mounting said top roll for rising and falling movements in a direction generally toward and from said cane and bagasse rolls, and means to move said top roll laterally to maintain the ratio between said openings substantially constant regardless of movements of said top roll, said means comprising a cylinder, a piston in said cylinder actuated by rising movement of the top roll, means responsive to movement of said piston to move the top roll laterally in an amount proportional to the movement of the piston, a housing having a portion in which said top roll is mounted, said housing portion being inclined with respect to the vertical and said housing being pivotally mounted for swinging movement in a generally lateral direction.

10. A cane mill having a cane roll and a bagasse roll and housings in which the ends of said rolls are mounted, a top roll and housings in which said top roll is mounted, said last-named housings being mounted for lateral movement relatively to the first housings, said top roll being mounted for rising and falling movement in its housings, hydraulic means applying pressure to said top roll to control such rising and falling movement comprising a follower member actuated by the top roll in such movements in its housings, and means responsive to the actuation of said member to move said top roll housings laterally.

11. A cane mill having a cane roll and a bagasse roll and housings in which the ends of said rolls are mounted, a top roll and housings in which said top roll is mounted, said last-named housings being mounted for lateral movement relatively to the first housings, actuating means to effect such lateral movement, said top roll being mounted for rising and falling movement in its housings, and means responsive to said last-named movement to operate said actuating means.
